DESIGN FOR A DRESS

Viola Mayer Berrick, New York, N. Y.

Application October 6, 1937, Serial No. 71,985

Term of patent 3½ years

To all whom it may concern:

Be it known that I, Viola Mayer Berrick, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the application and particular arrangement of loopings caught under tucks, on the dress as shown.

I claim:

The ornamental design for a dress, substantially as shown and described.

VIOLA MAYER BERRICK.
